UNITED STATES PATENT OFFICE.

ROBERT H. BLEVINS, OF BRISTOL, TENNESSEE, ASSIGNOR OF ONE-FOURTH TO JAMES A. DICKEY, OF BRISTOL, TENNESSEE, AND ONE-FOURTH TO C. L. T. FISHER, OF WASHINGTON, DISTRICT OF COLUMBIA.

HYDRAULIC POWER UNIT.

1,202,657.

Specification of Letters Patent. Patented Oct. 24, 1916.

Application filed June 21, 1915. Serial No. 35,402.

To all whom it may concern:

Be it known that I, ROBERT H. BLEVINS, a citizen of the United States, and resident of Bristol, in the county of Sullivan and State of Tennessee, have invented certain new and useful Improvements in Hydraulic Power Units; and I do hereby declare the following to be a full, clear, and exact description of the invention, such as will 5 enable others skilled in the art to which it appertains to make and use the same.

My invention relates to a hydraulic power unit, and particularly to that type of unit in which a blade wheel supporting and 15 water guiding structure is located in the bed of a flowing stream or river, and carries a plurality of buoyant blade wheels connected in driving relation, one with the other, for simultaneous rotary movement by 20 the current of the stream.

One object of my invention resides in the provision of novel blade wheel bearing mechanism, which enables the axis of the blade wheel to move in an upward direction 25 to compensate for the rise of the wheels resulting from the rise of the surface of the stream or river in which the power unit is located.

Another object of my invention resides in 30 the provision of a novel arrangement of gates controlling the flow of the stream so as to efficiently operate the wheels, or to cut off the supply when it is desired to prevent the wheels from operating, and to still 35 further deflect any sand and drift wood so that they do not enter the wheel flume.

Other objects of my invention will appear 40 from the following description, taken in connection with the accompanying drawings in which I have illustrated one preferred embodiment of my invention.

In the drawings: Figure 1 is a side elevation 45 view of one form of hydraulic power unit constructed according to my invention. Fig. 2 is a plan view of the same. Fig. 3 is a central section view on the line 3—3 of Fig. 2. Fig. 4 is a detail view showing the bearing mechanism. Fig. 5 is a section on the line 5—5 of Fig. 4. Fig. 6 is a section 50 on the line 6—6 of Fig. 4. Fig. 7 is a

diagrammatic view showing one of the hydraulic power units located in the bed of a river or stream.

The hydraulic power unit, as shown, consists of a wheel supporting and water guiding structure, comprising the river bed 1 and three vertical parallel walls 2, 3 and 4, respectively. The entire structure is preferably constructed of reinforced concrete. The space between the walls 2 and 3 is the 55 normal path of flow of the river or stream, and the entire structure is so located in the river or stream that the fall thereof is utilized. The space between the walls 3 and 4 forms the wheel flume, and the flow of 60 water therethrough is controlled by a vertically movable gate 5 running in tracks 6 carried by the walls 3 and 4. This gate is connected with a shaft 7 by means of chains 8. The shaft 7 carries a crank 9 and a 65 ratchet wheel 10 engaged by a pawl 11' mounted on the wall 4, to hold the gate in any desired position. It will be evident from this construction that the gate 5 may be raised to admit water to the flume by 70 turning the crank 9 which winds chains 8 on shaft 7, thereby causing the gate to rise. At an obtuse angle to the gate 5, and extending across the river bed 1, is a wall or 75 dam 11, which is equal to the height of the low water level of the river, and serves to divert all of the water through the flume when desired. This wall or dam 11 is provided with a vertically sliding sluice gate 12, operated by a lever 13 which, when 80 raised, will prevent sand, or other refuse, from passing into the flume, and will permit it to pass through said gate and down the natural course of the river. Refuse, such as sand, is further prevented from 85 entering the flume by a low sand gate 14, substantially at right angles to the gate 12 and controlled by handle 15, which may be set in any desired position by means of the pawl and ratchet mechanism 17. The angle 90 between gates 12 and 14 serves to divert the sand and prevent it from passing through the flume, as before stated, where it might injure the wheel mechanism.

In order to prevent drift wood and other 100

buoyant refuse from passing into the flume, a buoyant boom 18 is chained at 19 to wall 2, and extends across the wheel supporting and water guiding structure in front of the 5 gates, so that all drift wood is deflected thereby and passes down the river bed 1 and is thereby prevented from injuring the wheels.

Below the gates, the walls 3 and 4 are 10 provided with three sets of wheel piers 20, 21 and 22, which carry the buoyant blade wheels. On each pier is mounted bearing mechanism for supporting the axles of the wheels, and since all of these bearing 15 mechanisms are similar in construction, only one of these will be herein described.

This mechanism consists of a horizontal plate 23 embedded in the concrete of the pier, and provided with a longitudinal dove-tailed groove 24. In this groove 24 is slidably mounted a base 25 carrying the uprights 26 of arcuate formation, and connected at the bottom by the base 25, the upper surface of which is inclined on a line 25 parallel with a radial line extending to the center of the next preceding wheel to form a seat for the wheel bearing shoe a^7 , which has formed integral therewith the bearing stand 28. On the top of the bearing stand 28, is a lug 29, and pivotally secured to this lug, as at 30, is a second shoe 31. These shoes are formed with bifurcated ends to engage and slide upon uprights 26. Thus when buoyant 35 blade wheels, whose axles are mounted in the bearing mechanism of that type above described, begin to float and rise, they are guided, in their upward movement, by the arcuate uprights 26. The axles 32 of the blade wheels 33 are each connected one with 40 the other by radius rods 34, which are adjustable, and the arc of the uprights 26 of each bearing mechanism is struck from the center of the next preceding wheel, the arc of the first upright members being taken 45 from the center of the shaft 35 carrying pulley 35', to which power is transmitted by the wheels 33 through the medium of interconnecting chains 36 running on sprockets 37, carried by the axles of the wheels. The ratio of the gearing between each wheel 33 is the same so that all of the wheels are simultaneously rotated, but the ratio of gearing 50 between the first wheel and the shaft 35 is slightly increased or decreased as may be deemed best, according to the flow of the river or stream in which the hydraulic power unit herein described is located. The uprights for the wheel, located directly behind the shaft 35 and moving about the shaft 35 55 as a center, are stationary, so that the drive from pulley 35' to this wheel will never become slack.

Each buoyant blade wheel 33 comprises an axle 32 upon which is mounted a buoyant drum 38 having two bands or hoops 39 there-

on, into which are tapped spoke supports 40 which are riveted at their ends to the rear surface of the curved blades 41 set into rings 42. These blades are so curved that in entering into the water they gradually fill up 70 without resistance, and in leaving the water are drawn out in a substantially vertical plane, and thus all of the time they are in the water they catch the full power of the current. Also the bed of the flume is hollowed out at 43 under each wheel, so that the full depth of the water in the flume is utilized and no power is wasted.

While I have herein described one specific embodiment of my invention, which I have 80 found in actual practice to give good results, it is to be understood that desirable modifications may be made therein without departing from the spirit and scope of my invention as herein set forth.

I claim:

1. A hydraulic power unit including a wheel flume, a plurality of rotatable blade wheels bodily movable relative to each other to compensate for varying heights of water, 90 and means spacing said wheels from each other and permitting each wheel to move through an arc having the axis of the next adjacent wheel as its center.

2. A hydraulic power unit including a 95 wheel flume, a plurality of rotatable blade wheels bodily movable relative to each other to compensate for varying heights of water, mechanism interconnecting said wheels for synchronous rotative movement, and means 100 spacing said wheels from each other and permitting each wheel to move through an arc having the axis of the next adjacent wheel as its center.

3. The combination in a hydraulic power 105 unit for location in the bed of a river to utilize the current of the latter, of a wheel supporting and water guiding structure including a passage located in the normal path of flow of the river and a wheel flume, a gate 110 controlling the water admitted to said flume, angularly disposed gates in front of said first mentioned gate and coöperating to prevent refuse from entering said flume, and manually operated means for independently 115 controlling each of said gates, substantially as described.

4. The combination in a hydraulic power 120 unit including a plurality of buoyant wheels, axles and bearing mechanism therefor comprising arcuate uprights, bearing stands for supporting the axles of said wheels and movable upwardly in said uprights, said uprights being mounted for longitudinal movement, and radius rods connecting the wheels 125 with each other to maintain the same in spaced operative relation, substantially as described.

5. The combination in a hydraulic power 130 unit including a plurality of buoyant wheels,

and bearing mechanism therefor comprising arcuate uprights, bearing stands for supporting the axles of said wheels and movable upwardly in said uprights, said uprights being mounted for longitudinal movement, radius rods connecting the wheels with each other to maintain the same in spaced

5 operative relation, and driving mechanism interconnecting said wheels for simultaneous rotary movement, substantially as described. 10

In testimony whereof I have signed this specification.

ROBERT H. BLEVINS.
